(57) **CLAIM**

The ornamental design for a stimulation device, as shown and described.

DESCRIPTION

FIG. 1 is a top front side perspective view of a stimulation device of the present invention;

FIG. 2 is a top view of the stimulation device of FIG. 1;
FIG. 3 is a bottom view of the stimulation device of FIG. 1;
FIG. 4 is a side view of the stimulation device of FIG. 1;
FIG. 5 is the other side view of the stimulation device of FIG. 1;

FIG. 6 is a rear view of the stimulation device of FIG. 1;
FIG. 7 is a front view of the stimulation device of FIG. 1; and,
FIG. 8 is a bottom rear perspective view of the stimulation device of FIG. 1.
